UNITED STATES PATENT OFFICE.

JOHN G. MILLER, OF CHAMPAIGN, ILLINOIS.

TRACE-CARRIER.

SPECIFICATION forming part of Letters Patent No. 425,235, dated April 8, 1890.

Application filed April 26, 1889. Serial No. 308,744. (No model.)

To all whom it may concern:

Be it known that I, JOHN G. MILLER, a citizen of the United States, residing at Champaign, Illinois, have invented certain new and useful Improvements in Trace-Carriers, of which the following is a specification.

My invention relates to a trace-carrier for harness which shall be simple in construction and operation and which is capable of being applied either to the back-strap or to the hip-strap of the harness, and which is adapted to securely retain the traces against accidental removal, while at the same time they may be easily taken out when desired.

In the drawings, Figure 1 is a plan view, and Fig. 2 a side elevation, of my improved trace-carrier applied to the back-strap of the harness.

In the drawings, A represents the back-strap, B the crupper-strap, and C the flap connecting the back-strap and the crupper-strap together, and serving as a guard to prevent contact of the trace-carrier with the back of the horse.

D is an arched bar, which may have its ends riveted, respectively, to the back-strap and crupper-strap when the carrier is to be connected to those parts.

d d represent studs, which are formed integrally with the arched bar D and projected downwardly therefrom, preferably on a level with the top of the back-strap and crupper-strap, and terminating in the flanged heads *d' d'*, whereby there is left a space between

the under faces of said heads and the flap C sufficient for the passage of the cockeyes E when the parts are in their normal position. When it is desired to suspend the traces, the cockeyes are forced between the heads *d* and the flap C, which is readily done because of the yielding character of the latter, and then the cockeye, by being turned slightly, can be slipped over said heads, and the weight of the trace will draw it back, so that the flanged heads will sustain the outer end of the cockeye, as clearly indicated by dotted lines in Fig. 1. If desired, this arched bar may be constructed with only a single stud, and when so formed one may be applied to each of the hip-straps or to other portions of the harness.

It is not essential that the hip-strap and crupper-strap be separately made, for if made integrally they may be made to take the place of the flap C.

I claim—

A trace-carrier consisting of a single bar having an upwardly-arched central portion and perforated ends to adapt it to be riveted to the harness-straps, and having an integral stud projecting from the under side of the arched portion and terminating in a flanged head, substantially as described.

JOHN G. MILLER.
